UNITED STATES PATENT OFFICE.

WARREN H. TAYLOR, OF STAMFORD, CONNECTICUT, ASSIGNOR TO THE
YALE & TOWNE MANUFACTURING COMPANY, OF SAME PLACE.

DESIGN FOR A KEY.

SPECIFICATION forming part of Design No. 25,309, dated March 31, 1896.

Application filed December 11, 1895. Serial No. 571,835. Term of patent 14 years.

To all whom it may concern:

Be it known that I, WARREN H. TAYLOR, a citizen of the United States, and a resident of Stamford, in the county of Fairfield and 5 State of Connecticut, have invented and produced a new and original Design for a Key, of which the following is a specification, reference being had to the accompanying drawings, forming part thereof, in which—

10 Figure I is a view of one side of a key, showing my design. Fig. II is a view of the opposite side of the same. Fig. III is a top view of the key in the position shown in Fig. I. Fig. IV is a bottom view of the key in the 15 same position. Fig. V is a view of the stem end of the key. Fig. VI is a view of the bow end of the key. Fig. VII is a cross-section of the stem.

The leading features of my design consist 20 in the trefoil bow, a round stem having a radial wing and a shank elliptical in cross-section, gradually tapering to the bow from a collar adjacent to the stem and gradually merging into the shank.

25 The key represented has a round stem provided with a radial wing. On the inner end of the stem is a shoulder providing a collar, which gradually merges into and from which

extends a gradually-tapering shank, which is of elliptical form in cross-section and leads 30 to a bow of trefoil shape having a panel, located within which is a trefoil figure in outline providing an inner panel, within which suitable lettering may be placed. The shank is shown with grooves in the sides thereof, 35 which also provide panels for suitable lettering.

Having thus described my invention, the following is what I claim as new therein and desire to secure by Design Letters Patent: 40

1. The design for a key; substantially as herein shown and described. 45
2. The design for a key having a shank elliptical in cross-section, gradually tapering from the stem to the bow and provided with a shoulder forming a collar gradually merging into the shank; substantially as herein shown and described.

3. The design for a key having a trefoil bow and a shank formed with a panel for suitable lettering; substantially as herein shown and described. 50

WARREN H. TAYLOR.
